UNITED STATES PATENT OFFICE.

MILTON F. CHESHIRE, OF CHICAGO, ILLINOIS, ASSIGNOR TO THOMAS A. CHESHIRE,
OF DES MOINES, IOWA.

ADDRESSING-MACHINE.

1,335,043.

Specification of Letters Patent. Patented Mar. 30, 1920.

Application filed November 29, 1918. Serial No. 264,564.

To all whom it may concern:

Be it known that I, MILTON F. CHESHIRE, a citizen of the United States, and a resident of the city of Chicago, county of Cook, and State of Illinois, have invented certain new and useful Improvements in Addressing-Machines, of which the following is a specification.

My invention relates to improvements in addressing machines, and has for its object the provision of an improved machine of this character which is simple and efficient in use, occupies but little floor space, and is capable of economical manufacture, the present invention constituting an improvement in the construction disclosed in the application of Carey A. Cheshire, filed January 19, 1917, Serial No. 143,350.

Other objects will appear hereinafter.

10 The invention consists in the combinations and arrangements of parts hereinafter described and claimed.

The invention will be best understood by reference to the accompanying drawings forming a part of this specification, and in which,

Figure 1, is a top plan view of a machine embodying the invention,

Fig. 2, a front view of the same,

Fig. 3, a longitudinal section through the discharge end of the machine,

Fig. 4, a detail view of a portion of printing mechanism employed in the machine,

Fig. 5, a plan view of a stop plate employed in the machine,

Fig. 6, a perspective view of a stencil receiving hopper employed in the machine,

Fig. 7, a detail view of mechanism employed for discharging stencils from the machine,

Fig. 8, a detached view of a discharge slide employed in said stencil discharging mechanism,

Fig. 9, a section taken on line 9—9 of Fig. 1,

Fig. 10, a detail view of the upper portion of a stencil discharging mechanism,

Fig. 11, a view taken at right angles to Fig. 10, and

Fig. 12, a detail view of a portion of the stencil discharging mechanism.

The preferred form of construction, as illustrated in the drawings, comprises a

feed table 13 having two longitudinal parallel feed slots 14 therein. A feeding mechanism 15 is arranged at the rear side of one end of table 13 to deposit articles, such as magazines or the like, to be addressed, singly on the feed table 13, such mechanism being well known and fully shown and described 55 in said application to Carey A. Cheshire. Feed chains 16 are arranged to travel under table 13, as indicated, and are provided with upstanding pins 17 traveling in the slots 14 and adapted to feed the said magazines 60 or other articles along the table 13 and onto a printing table 18 arranged beyond the range of pins 17. A strip 13'—18' is arranged longitudinally between the feed chains over said tables to maintain the articles in slightly arched relation, which facilitates the feeding thereof. The table 18 is operatively connected with screw threaded 70 adjusting shafts 18'', by means of which the height thereof may be adjusted with relation to suitable printing mechanism 19 co-operating therewith, said printing mechanism being in general old and well known and differing only from that disclosed in the aforesaid application of Carey A. Cheshire 75 in minor and unimportant details. A stencil supply hopper 20 is arranged to supply the usual stencils to the printing mechanism through the usual stencil guide 21 and a suitable feeding mechanism operable by 80 the oscillatory arm 22 is arranged to feed the stencils through the guide 21 to the printing mechanism 19 in the usual way. The stencils thus fed through the machine are discharged into a removable stencil receiving hopper 23 arranged at the rear of the machine, as indicated. To effect this, a reciprocatory slide 24 is arranged to engage the most advanced stencil in the guide-way 21 and draw the same rearwardly into the 85 upper end of the hopper 23, said slide 24 being connected by a link 25 with the upper end of an oscillatory arm 26 carrying roller 27 riding upon the periphery of a cam 28 on shaft 29 of the machine, a tension spring 100 30 serving to hold the roller 27 in such contact. A depressible platform 31 is arranged to receive and support the stencils as deposited in hopper 23 and travel downwardly 105 therein to accommodate the ever increasing pile or stack thereof. The platform 31 is

carried by a bracket 32 carrying a split nut 33 traveling on a threaded shaft 34, which serves to effect this downward feed. One-half of the nut 33 is carried by a spring held 5 arm or finger 35, and whereby the said platform may be released from the domination of shaft 34 and elevated, by hand, upon the filling of hopper 23.

A stop plate 36 is arranged under the 10 printing table 18 and provided with a plurality of threaded holes 37 adapted to receive stop pins 38, which are arranged to project upwardly through slots 39 in table 18, said stop pins being arranged and adapted 15 to contact with the edges of the articles being printed and properly position the same with relation to the printing mechanism 19, said articles being carried from the pins 17 by their own inertia until stopped 20 by contact with said pins 38. The stop plate 36 is carried by a vertical reciprocating rod 40, normally held in depressed relation by compression spring 41 but operable by rocker arm 42 carrying the roller 43 25 riding upon the periphery of a cam 44 on shaft 45 of the machine, and whereby the stop pins 38 are elevated at the proper time to engage and position the articles for printing and are depressed in order to release 30 said articles for discharge. Discharge chains 46 are arranged under table 18, and are provided with upstanding pins 47 traveling in slots 48 in table 18 and overlapping and parallel to slots 14 in table 13. 35 The pins 47 are positioned on chains 46 to operate well behind the pins 17 on chains 16, so as to permit of a pause in the feed of the articles for the printing operation, which is timed to take place during such 40 pause. Upon completion of the printing operation, the stop pins 38 are depressed at the same time that the corresponding set of pins 47 comes in contact with the rear edge of the article, and the printed article is thus 45 discharged from the machine. The discharged printed article passes over an apron 49 onto a removing conveyer 50, which is arranged transversely with reference to the direction of feed of chains 46 and 16, and 50 may be of any usual or desired construction. The printed articles are then removed, by hand, from the conveyer 50 in the usual manner.

The machine disclosed is a simple and efficient one for the purpose and is capable of economical manufacture, operating to discharge the articles with great efficiency and being simpler than the discharging mechanism employed in the machine disclosed in 55 said application of said Carey A. Cheshire.

While I have illustrated and described the preferred form of construction for carrying my invention into effect, this is capable of variation and modification without departing 60 from the spirit of the invention. I,

therefore, do not wish to be limited to the precise details of construction set forth, but desire to avail myself of such variations and modifications as come within the scope of the appended claims.

Having described my invention, what I claim as new and desire to secure by Letters Patent is:

1. A machine of the class described comprising printing mechanism; an endless feed conveyer having feed pins thereon arranged to feed articles to said printing mechanism and release them; and a discharge endless conveyer having feed pins thereon and operating in the same general direction as said feed conveyer, the pins on said discharge conveyer being set to operate on said articles at a later time than the pins on said feed conveyer, substantially as described. 75

2. A machine of the class described comprising printing mechanism; a feed conveyer in the form of two chains having feed pins thereon, arranged to feed articles to said printing mechanism and release them; and a discharge conveyer in the form of chains having feed pins thereon and operating in the same general direction as said feed conveyer, the pins on said discharge conveyer being set to operate on said articles 80 at a later time than the pins on said feed conveyer, substantially as described. 90

3. A machine of the class described comprising printing mechanism; a feed conveyer in the form of two chains having feed pins thereon, arranged to feed articles to said printing mechanism and release them; a removable stop arranged to stop said articles in position to be printed; and a discharge conveyer in the form of chains having feed pins thereon and operating in the same general direction as said feed conveyer, the pins on said discharge conveyer being set to operate on said articles at a later time than the pins on said feed conveyer, substantially as described. 100 105

4. A machine of the class described comprising printing mechanism; a feed conveyer in the form of two chains having feed pins thereon, arranged to feed articles to said printing mechanism and release them; a discharge conveyer in the form of chains having feed pins thereon, and operating in the same general direction as said feed conveyer, the pins on said discharge conveyer being set to operate on said articles at a later time than the pins on said feed conveyer; and a third conveyer arranged to receive articles from said discharge conveyer and remove the same, substantially as described. 115 120 125

5. A machine of the class described comprising printing mechanism; a feed conveyer in the form of two chains having feed pins thereon arranged to feed articles 130

to said printing mechanism and release them; a removable stop arranged to stop articles in position to be printed; a discharge conveyer in the form of chains having feed pins thereon and operating in the same general direction as said feed conveyer, the pins on said discharge conveyer being set to operate on said articles at a later time than the pins on said feed conveyer; and a third conveyer arranged to receive articles from said discharge conveyer and remove the same, substantially as described.

6. A machine of the class described comprising printing mechanism; a conveyer arranged to feed articles to said printing mechanism; a discharge conveyer operating in the same general direction as said feed conveyer, but operating on each of said articles at a later time; and a third conveyer arranged at right angles to and adapted to receive articles from said discharge conveyer and remove the same, substantially as described.

7. A machine of the class described comprising printing mechanism; a feed conveyer arranged to feed articles to said printing mechanism and release them; a removable stop arranged to stop said articles in position to be printed; a discharge conveyer operating in the same general direction as said feed conveyer, but operating on each article at a later time; and a third conveyer arranged at right angles to and adapted to receive articles from said discharge conveyer and remove the same, substantially as described.

8. A machine of the class described comprising printing mechanism; a feed conveyer in the form of two chains having feed pins thereon arranged to feed articles to said printing mechanism and release them; a discharge conveyer in the form of chains, having feed pins thereon and operating in the same general direction as said feed conveyer, the pins on said discharge conveyer being set to operate on said articles at a later time than the pins on said feed conveyer; and a third conveyer arranged at right angles to and adapted to receive articles from said discharge conveyer and remove the same, substantially as described.

9. A machine of the class described comprising printing mechanism; a feed conveyer in the form of two chains having feed pins thereon, arranged to feed articles to said printing mechanism and release them; a removable stop arranged to stop said articles in position to be printed; a discharge conveyer in the form of chains having feed pins thereon and operating in the same general direction as said feed conveyer, the pins on said discharge conveyer being set to operate on said articles at a later time than

the pins on said feed conveyer; and a third 65 conveyer arranged at right angles to and adapted to receive articles from said discharge conveyer and remove the same, substantially as described.

10. A machine of the class described comprising printing mechanism; a feed conveyer in the form of two chains having feed pins thereon arranged to feed articles to said printing mechanism and release them; a discharge conveyer in the form of chains 70 having feed pins thereon and operating in the same general direction as said feed conveyer, the pins on said discharge conveyer being set to operate on said articles at a later time than the pins on said feed conveyer; and stencil feeding and discharging mechanism for said printing mechanism, substantially as described.

11. A machine of the class described comprising printing mechanism; a conveyer arranged to feed articles to said printing mechanism; a discharge conveyer operating in the same general direction as said feed conveyer, but operating on each of said articles at a later time; a third conveyer arranged to receive articles from said discharge conveyer and remove the same; and stencil feeding and discharging mechanism for said printing mechanism, substantially as described.

12. A machine of the class described comprising a feed table having two parallel longitudinal slots therein; means for depositing articles to be printed on said feed table; feed chains arranged under the slots 100 in said table; feed pins on said chains projecting upwardly through the slots in said table; a printing table arranged at the discharge end of said feed table and having two longitudinal slots therein, the slots in 105 said printing table overlapping the slots in said feed table; printing mechanism co-operating with said printing table; discharge chains arranged under the slots in said printing table and having pins projecting upwardly therethrough, the pins on said discharge chains being set to operate on said articles at a later time than the pins on said feed chains; and removable stops for said printing table arranged to stop said articles in position to be printed, substantially 110 as described.

13. A machine of the class described comprising a feed table having two parallel longitudinal slots therein; means for depositing articles to be printed on said feed table; feed chains arranged under the slots in said table; feed pins on said chains projecting upwardly through the slots in said table; a printing table arranged at the discharge end of said feed table and having two longitudinal slots therein, the slots in 120 said printing table overlapping the slots in said printing table.

said feed table; printing mechanism co-operating with said printing table; discharge chains arranged under the slots in said printing table and having pins projecting upwardly therethrough, the pins on said discharge chains being set to operate said articles at a later time than the pins on said feed chains; and removable adjustable stops for said printing table, arranged to stop said articles in position to be printed, substantially as described.

14. A machine of the class described comprising a feed table having two parallel longitudinal slots therein; means for depositing articles to be printed on said feed table; feed chains arranged under the slots in said table; feed pins on said chains projecting upwardly through the slots in said table; a printing table arranged at the discharge end of said feed table and having two longitudinal slots therein, the slots in said printing table overlapping the slots in said feed table; printing mechanism co-operating with said printing table; discharge chains arranged under the slots in said printing table and having pins projecting upwardly therethrough, the pins on said discharge chains being set to operate said articles at a later time than the pins on said feed chains; removable stops for said printing table, arranged to stop said articles in position to be printed; and a removing conveyer arranged to transversely cross the discharge end of said printing table, substantially as described.

charge end of said printing table, substantially as described.

35

15. A machine of the class described comprising a feed table having two parallel longitudinal slots therein; means for depositing articles to be printed on said feed table; feed chains arranged under the slots in said table; feed pins on said chains projecting upwardly through the slots in said table; a printing table arranged at the discharge end of said feed table and having two longitudinal slots therein, the slots in said printing table overlapping the slots in said feed table; printing mechanism co-operating with said printing table; discharge chains arranged under the slots in said printing table and having pins projecting upwardly therethrough, the pins on said discharge chains being set to operate said articles at a later time than the pins on said feed chains; removable adjustable stops for said printing table, arranged to stop said articles in position to be printed; and a removing conveyer arranged to transversely cross the discharge end of said printing table, substantially as described.

In testimony whereof I have signed my name to this specification in the presence of two subscribing witnesses.
